(57) **CLAIM**

The ornamental design for a triple claw corner hammer, as shown and described.

DESCRIPTION

FIG. 1 is an isometric view of a triple claw corner hammer; FIG. 2 is a front view thereof; FIG. 3 is a rear view thereof; FIG. 4 is a left side view with a right side view being the mirror image thereof; FIG. 5 is a top view thereof; and, FIG. 6 is a bottom view thereof.

The broken lines in FIGS. 1-4 illustrate a handle which forms no part of the claimed design.
